ALFRED MENDEL AND ERNST KLEINMANN, OF BERLIN-LICHTENBERG, GERMANY

HAIR SLIDE

Application filed February 11, 1931, Serial No. 515,066, and in Germany September 22, 1930.

This invention relates to hair slides which consist of two limbs between which hair can be gripped. In such slides it has already been proposed to provide one limb or bow with serrations or little teeth which on closing of the slide are forced against the other limb or clasp bow or through openings in the latter so that the hair is gripped firmly between the limbs. It is found, however, that such constructions do not always lead to the desired result, and the object of the present invention is to provide an improved slide in which particularly firm gripping of the hair may take place.

According to the present invention two series of teeth are provided, one being fixed and the other being movably mounted in the slide so that with the slide closed the two series of teeth co-operate to grip the hair firmly but with the slide open they will release the hair.

In carrying the invention into effect it is preferred to make one limb of the slide boat-shaped, this limb carrying the fixed teeth and containing a member carrying the movable teeth and mounted to slide within the boat-shaped limb.

In order that the invention may be clearly understood and readily carried into effect, some constructions in accordance therewith will now be described by way of example with reference to the accompanying drawings, in which

Figure 1 shows one form of slide;

Figure 2 is a cross-section on the line II—II of Figure 1;

Figure 3 shows a modified form of slide;

Figure 3a shows diagrammatically the position of the teeth with the slide shown in Figure 3 open, while

Figure 3b shows the position of the same teeth when the slide is closed.

Figure 4 is a cross-section on the line IV—IV of Figure 3, and

Figure 5 shows separately the clasp limb or bow of the slides of Figures 1 and 3.

Referring first to Figures 1 and 2, the slide comprises a boat-shaped limb 1 and a clasp limb or bow 2 which is pivotally connected to the limb 1 at 11. The fixed teeth

4 are formed integral with and project upwards from the centre line of the boat-shaped limb 1. A member 3 carrying teeth 5 is inserted within the trough of the boat-shaped member 1 and is formed with slots 6 through which the teeth 4 project. This member 3 can slide within the limb 1 within certain limits determined by the engagement of the teeth 4 with the ends of the slots 6 or by engagement with the ends of the member 3 with the ends of the limb. The member 3 is prevented from falling out of the boat-shaped limb 1 by the bending over of the longitudinal edges of the limb as shown at 16 in Figure 2.

The teeth 4 and 5 are so disposed that when the slide is open there is room for hair to be inserted between the teeth. In order to move the member 3 into a suitable position for this on the opening of the hair slide, the clasp bow or limb 2 is provided with a cam or like projection 10 which engages the end of the member 3 and moves it longitudinally within the boat-shaped limb 1 as the clasp bow 2 is swung about its pivot 11. On the closing of the clasp bow 2 an opening 17 which is made in it engages over a cam-like retaining hook 7 which is integral with the member 3, and the co-operation of the side of the opening with the hook serves to push the member 3 towards the right as seen in Figure 1. This causes the teeth 5 to approach the stationary teeth 4 so that the hair is firmly gripped between the teeth. The member 3 can, of course, move towards the right since the cam-like projection 10 moves right as the clasp bow is closed.

Referring now to the constructions shown in Figures 3 and 4, as before the clasp bow 2 is pivotally connected to the boat-shaped limb 1, but the fixed teeth 4 are fashioned from the side walls of the limb 1 so that the teeth 5 on the member 3 slide between the fixed teeth. The teeth are so disposed that when the clasp bow 2 is open the movable teeth accurately register with the fixed teeth 4 as shown in Figure 3a, but that when the clasp bow 2 is closed the teeth 5 take up the position shown in Figure 3b.

A spring 8 is provided within the boat-

shaped limb 1 to bear against the end of the sliding member 3, this spring tending to force the member towards the right and thus to retain the latter in the desired end position. In order, however, to ensure the movement of the sliding member 3 to the right on the closing of the clasp bow 2, a ball shaped cam 9a is provided on the member 3 to co-operate with the opening 17 in the 10 clasp bow 2. The opening 17 is so shaped that when the clasp bow 2 is pushed over the cam 9a the latter together with the whole sliding member 3 must yield towards the right.

15 In the constructions shown in Figures 3 and 4 the sliding member 3 is prevented from falling out by turning over parts of the side walls between the teeth 4 as shown at 16 in Figure 4. An additional ball-shaped 20 cam may be provided as shown at 9b to co-operate with the end of the main opening in the clasp bow to force the sliding member 3 to the left. This cam 9b may be employed either to effect some movement of the sliding member 3 before the action of the cam-like projection 10 begins, or it may be employed instead of the latter.

In order to avoid the use of excessive force when cams such as that shown at 9a are employed, the sides 12 and 13 of the clasp bow 2 are made curved and slightly resilient, and the cross-connection 18 which is provided to form the end of the opening 17 is slotted. Thus when the head of the cam 9a engages 35 in the opening 17 the sides 12 and 13 can bend slightly outwards.

It is, of course, clear that modifications may be made in the constructions shown by way of example. Thus a spring such as that 40 shown at 8 may be employed in the construction shown in Figure 1. Obviously also any arrangement of the fixed and movable teeth is possible and the number of them is chosen in accordance with the amount of gripping 45 action desired.

Having now particularly described and ascertained the nature of our said invention and in what manner the same is to be performed, we declare that what we claim is:—
50 1. In a hair slide comprising two limbs hinged together, the combination of two series of teeth, one series being fixed in said slide and the other being movable therein, and means actuated upon the opening and 55 closing of said limbs for moving said movable teeth to bring them on the closing of the limbs into a position in which they co-operate with said fixed teeth to grip firmly hair lying between said fixed teeth but on the 60 opening of the limbs to bring said movable teeth into a position in which they allow of release of said hair.

2. A hair slide comprising the combination of two limbs hinged together, one of 65 said limbs being trough-shaped and having

a series of integral teeth, a member mounted to slide within said trough-shaped limb and having a series of integral teeth, and means for causing said member to slide within said trough-shaped limb, said means being actuated upon the closing of the two limbs to bring the teeth upon said movable member into a position in which they co-operate with the teeth on said trough-shaped limb to grip firmly hair lying between said last-mentioned teeth and being actuated upon the opening of the two limbs to bring said movable member into a position in which the teeth thereon allow of release of said hair. 70 75

3. A hair slide comprising the combination of two limbs hinged together, one of said limbs being trough-shaped and having a series of integral teeth, a member mounted to slide within said trough-shaped limb and having a series of integral teeth, means actuated upon the closing of the two limbs to bring the teeth upon said movable member into a position in which they co-operate with the teeth on said trough-shaped limb to grip firmly hair lying between said last-mentioned teeth, and cam means carried by the second of said limbs and actuated upon the opening of the two limbs to bring said movable member into such a position that the teeth thereon allow of release of said hair. 80 85 90

4. A hair slide comprising the combination of two limbs hinged together, one of said limbs being trough-shaped and having a series of integral teeth, a member mounted to slide within said trough-shaped limb and having a series of integral teeth, spring means urging said member to slide within said trough-shaped limb into a position in which the teeth of said member co-operate with the teeth of said trough-shaped limb to grip firmly hair lying between said last-mentioned teeth, and cam means carried by the second of said limbs and actuated upon the opening of the two limbs to bring said movable member into such a position that the teeth thereon allow of release of said hair. 95 100 105

5. A hair slide comprising the combination of two limbs hinged together, one of said limbs being trough-shaped and having a series of integral teeth, a member mounted to slide within said trough-shaped limb and having a series of integral teeth, the other of said limbs being slotted and resiliently formed and constituting a clasp limb, cam means integral with the said movable member and co-operating with said slotted clasp limb upon engagement therewith to cause said movable member to slide into a position in which the teeth thereon co-operate with the teeth of said trough-shaped limb to grip firmly hair lying between said last-mentioned teeth, and means operative upon the opening of the two limbs to bring said movable member into a position in which the teeth thereon allow of release of said hair. 110 115 120 125 130

6. A hair slide comprising the combination of two limbs hinged together, one of said limbs being trough-shaped and having a series of integral teeth, a member mounted to slide within said trough-shaped limb and having a series of integral teeth, the other of said limbs being slotted and resiliently formed and constituting a clasp limb, cam means integral with the said movable member and co-operating with said slotted clasp limb upon engagement therewith to cause said movable member to slide into a position in which the teeth thereon cooperate with the teeth of said trough-shaped limb to grip firmly hair lying between said last-mentioned teeth, and additional cam means carried by said movable member, also co-operating with said slotted clasp limb and operative upon the opening of the two limbs to bring said movable member into a position in which the teeth thereon allow of the release of said hair. 70
7. A hair slide comprising the combination of two limbs hinged together, one of said limbs being trough-shaped and having a series of teeth fixed along the centre line of the trough, a slotted movable member mounted to slide within said trough-shaped limb, the arrangement being such that the teeth of said trough-shaped limb project through the slots in said movable member, said movable member also having a series of integral teeth, and means for causing said member to slide within said trough-shaped limb, said means being actuated upon the closing of the two limbs to bring the teeth upon said movable member into a position in which they co-operate with the teeth on said trough-shaped limb to grip firmly hair lying between said last-mentioned teeth and being actuated upon the opening of the two limbs to bring said movable member into a position in which the teeth thereon allow of release of said hair. 80
8. A hair slide comprising the combination of two limbs hinged together, one of said limbs being trough-shaped and having a series of teeth formed as projections in the side walls of the trough-shaped limb, a member also having a series of integral teeth and mounted to slide to and fro within said trough-shaped limb, and means for causing said member to slide within said trough-shaped limb, said means being actuated upon the closing of the two limbs to bring the teeth upon said movable member into a position in which they co-operate with the teeth on said trough-shaped limb to grip firmly hair lying between said last-mentioned teeth and being actuated upon the opening of the two limbs to bring said movable member into a position in which the teeth thereon allow of release of said hair. 90
9. A hair slide comprising a main limb, a clasp limb, a hinge connecting said clasp limb to said main limb substantially at one end thereof, a movable member slidably at- 100
- tached to said main limb and having sliding freedom in a plane containing said main limb and said clasp limb, teeth on said main limb and teeth on said movable member, all said teeth projecting towards said clasp limb, catch mechanism for fastening said clasp limb close to said main limb, means upon said clasp limb operative, when said clasp limb is close to said main limb, to hold said movable member fixed relatively to said main limb in a position in which the teeth of said movable member co-operate with the teeth of said main limb to grip firmly hair lying between said last-mentioned teeth, a projection on said clasp limb on the side of said hinge remote from the main body of said clasp limb and operative when said clasp limb is swung away from said main limb to move said movable member into a position in which the teeth thereon allow of release of said hair. 105
10. A hair slide comprising a main limb, a clasp limb hinged substantially at one end of said main limb, a movable member slidably attached to said main limb and having sliding freedom in a plane containing said main limb and said clasp limb, teeth on said main limb and teeth on said movable member, all said teeth projecting towards said clasp limb, catch mechanism, operative when said clasp limb is close to said main limb, for fastening said clasp limb to said movable member and holding it in a position in which the teeth of said movable member co-operate with the teeth of said main limb to grip firmly hair lying between said last-mentioned teeth and means upon said clasp limb operative when said movable member is swung away from said main limb to move said movable member into a position in which the teeth thereon allow of release of said hair. 110
